UNITED STATES PATENT OFFICE.

HUBERT GEORGE DRISCOLL, OF ST. JOHN'S, NEWFOUNDLAND.

NONFILLABLE BOTTLE.

Application filed September 10, 1928. Serial No. 304,927.

This invention relates to certain new and useful improvements in a non-fillable bottle. Its primary object is to provide a sure and simple means of preventing the bottle 6 from being refilled after its original contents have been removed. With this object in view, as will appear as the description proceeds, the invention consists in the novel construction and arrangement of parts as herein- 10 after more specifically set forth, claimed and shown in the accompanying drawings forming a part of the present application and in which:

Fig. 1 is a view of the bottle with a cut 15 away section showing the interior mechanism.

Fig. 2 is a sectional plan view.

Referring more in detail to the drawings in which similar reference characters des- 20 ignate corresponding parts throughout, it will be seen that the bottle 3 has a circular flange 4 on the inner side of the neck, and immediately above this flange is a cross piece 5 similarly made into the bottle neck. Into the 25 center of the flange 4 is fastened a flanged ring 6. A circular trapdoor shaped member 7 is hinged to this ring at 8 thus forming the complete check valve. Through the center of the check 7, a wire or string 9 is fastened 30 having on the lower end a weight 10 which may be a metal or glass ring or some other suitable shaped weight. This weight will cause the check 7 to close when the bottle is in any upright or horizontal position providing that the weight is not low enough to touch 35 the sides when the bottle is in a horizontal position. To the top of the check 7 a string

11 is loosely fastened the purpose of this string is to hold the check up while the bottle is being filled, and is fastened in such a manner that it may be withdrawn entirely when the bottle has been filled. The cross-piece 5 is to prevent the check 7 from opening too far and to prevent the mechanism from being otherwise tampered with.

It is believed that the construction and advantages of the structure shown may be apparent from the foregoing paragraphs taken in connection with the accompanying drawings without further detailed description.

While the preferred embodiment of the invention has been disclosed it is understood that minor changes in the details of construction, combination and arrangement of cooperating elements may be resorted to within the scope of what is claimed, without departing from the spirit of the invention.

What I claim:

In a bottle, an annular flange disposed within the neck thereof; said flange being integral with said neck and inwardly directed therefrom; a ring bearing with the margin of said flange, said ring adapted to constitute a seat; a flap-valve hinged to said ring in a manner to bear upon and coact with said seat; a weight suspended from said flap to normally close the same and a cross-piece disposed within said neck and integral therewith, said cross-piece being positioned above said flap-valve in a manner to limit the opening movement of the flap as and for the purpose specified.

In testimony whereof I affix my signature.
HUBERT GEO. DRISCOLL.
